UNITED STATES PATENT OFFICE.

CHARLES M. HEETER, OF BUTLER, PENNSYLVANIA.

OIL-WELL PACKER.

Application filed June 21, 1923. Serial No. 646,822.

To all whom it may concern:

Be it known that I, CHARLES M. HEETER, a citizen of the United States, residing at Butler, county of Butler, State of Pennsylvania, have invented a new and useful Improvement in Oil-Well Packers, of which the following is a full, clear, and exact description.

The present invention relates broadly to 10 oil well equipment, and more particularly to a packer adapted to form a tight joint between the casing and the wall of the hole.

At the present time, with certain earth formations or sands of different characters, 15 considerable difficulty is experienced in producing a tight joint around the casing as required. If a small area only of the wall is engaged, the earth at the point of engagement tends to break away, and the use of 20 packings having large packing areas has not proven feasible with apparatus heretofore available.

By the present invention, there is provided an improved form of packing adapted 25 to contact with a much greater wall area than has heretofore been possible, thereby enabling a tight joint to be easily produced.

In the accompanying drawings, there are shown, for purposes of illustration only, certain 30 embodiments of the present invention, it being understood that the drawings do not define the limits of my invention, as changes may obviously be made therein without departing from the spirit of the invention or scope of my broader claims.

In the drawings:

Fig. 1 is a side elevation of a portion of 40 an oil well packer in position within a well, the packing being expanded into engagement with the well wall;

Fig. 2 is a vertical section, on an enlarged scale, on the line II—II of Fig. 1, the packing sleeve, however, not being expanded;

Fig. 3 is a detail sectional view through 45 the joint provided between the packing carrying tube and the casing;

Fig. 4, is a vertical section, on an enlarged scale, on the line IV—IV of Fig. 1;

Fig. 5 is a detail sectional view of one 50 side of the lower end of the packer illustrated in Figs. 1 and 2; and

Fig. 6 is a view similar to Fig. 5, illustrating a slightly modified embodiment of the invention.

In carrying out the present invention, there is preferably provided a packing car-

rying tube 2, which may be of any desired length, and which is adapted to carry a rubber packing sleeve 3. In accordance with this invention, I have found that a packing sleeve substantially 6 feet in length may be advantageously used, although it will be apparent that this length may vary in accordance with the requirements.

Around the packing carrying tube 2, adjacent each end of the rubber sleeve 3, is a fabric ring 4. These rings are preferably formed by the use of comparatively narrow strips of burlap wound around the tube spirally, as clearly shown in Fig. 1. These fabric rings form abutments for the opposite ends of the sleeve and effectively prevent the same from slipping out of position.

The lower fabric ring 4 abuts at its lower end against a casing support 5, which may be threaded into position on the lower end of the tube 2. The upper edge of the top ring 4 in like manner abuts against the lower end of a ring 6, slidably mounted on the upper end of the tube 2 and held thereon against accidental removal by a collar 7. The tube 2, together with the associated parts may be secured to the lower end of the casing 8 by threading the bottom section of the casing onto the ring 6. On lowering the casing into position, the upper end of the ring 6 will abut against the lower end of the collar 7 and will carry the weight of the packer without exerting any compressing action on the packing sleeve 3. As

soon, however, as the support 5 engages the desired point 9 within the well, the further downward movement of the tube 2 is checked and thereafter lowering of the casing will cause the ring 6 to bear against the upper ring 4 and to force the same downwardly.

This downward movement will initially tend to place the packing sleeve under compression, whereby it is expanded outwardly throughout the major portion of its length, as clearly shown in Fig. 1, into engagement with the wall of the well. The continued downwardly movement will cause the fabric rings 4 to become compressed. This com-

pressing of the rings will cause the angle of the spirals to decrease, whereoy the strips will extend more nearly circumferentially of the tube 2. This will tend to provide an excess of this fabric material, enabling same to bulge outwardly to such an extent that it is impossible for the ends of the rubber packing sleeve to slip thereover. It will

be apparent that a similar action occurs at each end of the tube 2.

In some instances it is desirable to provide the support 5' for the lower end of the tube 2' with a tapered exterior, as clearly indicated in Fig. 6. Such a construction permits the lower fabric ring 4' to slip downwardly over the upper portion of the support until it jams into position and expands to an extent to form the desired abutting shoulder for the rubber sleeve 3'.

In Fig. 4 there is illustrated one form of joint which may advantageously be used between adjacent sections of the casing. This particular construction, however, may be varied as desired, or as found necessary. It comprises threading one end of each section 8 interiorly and the other end exteriorly and providing a coupling 10 to unite the adjacent ends of two casing sections.

The advantages of the present invention arise from the provision of a packing carrying tube having fabric rings thereon adjacent opposite ends of a packing sleeve, whereby expansion of the packing rings will effectively hold the packing sleeve in position. Still further advantages of the invention arises from the provision of packing rings constructed of strips of suitable

material wound spirally upon the packing 50 carrying tube.

I claim:

1. In a well packer, a packing carrying tube, spaced fabric rings thereon, and a rubber sleeve intermediate said rings, substantially as described.

2. In a well packer, a packing carrying tube, spaced rings thereon formed of a plurality of spirally wound layers of material, and a rubber sleeve intermediate said 40 rings, substantially as described.

3. In a well packer, a packing carrying tube, spaced fabric rings thereon, a rubber sleeve intermediate said rings, and a means for effecting a relatively longitudinal movement between said rings to expand said sleeve, substantially as described.

4. In a well packer, a rubber packing sleeve, means carrying said sleeve, and means co-operating with opposite ends of 50 said packing sleeve and comprising superimposed layers of spirally wound material for holding the ends of the packing sleeve in position, substantially as described.

In testimony whereof I have hereunto set 55 my hand.

CHARLES M. HEETER.
